(57) **CLAIM**

The ornamental design for a circular saw, as shown and described.

DESCRIPTION

FIG. 1 is a front perspective view of a circular saw showing the new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is a rear perspective view of a second embodiment of the circular saw showing a skyhook attachment.

The broken lines that define the bounds of the claimed design form no part thereof.

The broken lines shown in drawings form no part of the claimed design.

1 Claim, 6 Drawing Sheets
